J. W. STEWART

PUMP PLUNGER AND CROSSHEAD

Filed July 20, 1923

UNITED STATES PATENT OFFICE.

JOHN W. STEWART, OF MARTINSBURG, WEST VIRGINIA.

PUMP PLUNGER AND CROSSHEAD.

Application filed July 20, 1923. Serial No. 652,824.

To all whom it may concern:

Be it known that I, JOHN W. STEWART, a citizen of the United States, residing at Martinsburg, in the county of Berkeley and 5 State of West Virginia, have invented new and useful Improvements in Pump Plungers and Crossheads, of which the following is a specification.

This invention relates to improvements in 10 plungers and cross heads, and particularly to a non-corrosive-plunger preferably having a porcelain body and other advantageous structural accessories embodied therein.

The primary object of the invention is to 15 provide a porcelain plunger which is specially adapted for use in pump cylinders and ground to fit the cylinder in which it is disposed and also having a cross head attached thereto in a novel manner for 20 the general purpose of resisting wear or cutting of the parts by emery, silt and other analogous eroding materials when used in a pump cylinder for operating in connection with a fluid or a liquid containing erosive 25 or other constituents which injuriously affect the usual metal type of plungers, and also to so organize the parts of the improved plunger that it will take up contraction or expansion and avoid injury to and 30 breakage of various parts thereof. A further object of the invention is to generally improve plungers of the non-corrosive type and to comparatively simplify the structure thereof, particularly in the general assembly 35 of the several components, to insure strength and durability as well as efficiency in operation.

With these and other objects and advantages in view, the invention consists in the 40 preferred construction and arrangement of the several parts which will be more fully hereinafter described and claimed.

In the drawings:

Fig. 1 is a longitudinal vertical section 45 of a plunger, showing the cross head connected thereto and embodying the features of the invention.

Fig. 2 is a section through the cross head 50 and a portion of the plunger taken in a plane at right angles to that shown in Fig. 1;

Fig. 3 is a transverse vertical section on the line 3—3, of Fig. 1; and

Fig. 4 is an end elevation of the cross

head, showing the terminal and securing means for the plunger located therein. 55

The numeral 5 designates a porcelain cylinder, which serves as the exposed body portion of the plunger and is fitted at one extremity in a seat 6 formed in one end of a cross head 7. Extending through the center of the bore 8 of the porcelain cylinder 5 is an elongated bolt 9, preferably formed of bronze and having throughout the greater portion of its length spiral corrugations or 60 grooves 10. At the outer end of the bolt 9 is a head 11, which may be connected thereto in any suitable manner or formed as a part thereof. The inner extremity of the bolt 9 projects outwardly from the inner end of the cylinder 5 through a bore or opening 12 formed in the center of the cross head and opening into the center of the seat 6, the inner end of the said bolt being screw-threaded, as at 13, to receive a securing nut 14, which is firmly screwed against the 65 inner end wall 15 of the opening 16 of the cross head, the said opening 16 continuing through the opposite end of said cross head. The bolt 9 is rigidly secured in the bore 8 of the cylinder 5 by a cement filling 17, 70 which is closely packed in the bore 8 around the bolt and enters the grooves 10. The cement filling 17 continues throughout the 75 length of the cylinder bore, as clearly shown by Fig. 1, and serves to strengthen the porcelain cylinder 5 and also acts as a key means for rigidly holding the bolt 9 in central position in the cylinder and against rotative or 80 loose movement. Between the head 11 of the bolt 9 and the adjacent outer end of the cylinder 5 is a non-corrosive washer 18, preferably 85 formed of lead, and between the inner end of the porcelain cylinder and the end wall of the seat 6 is a wood fiber washer 19. The washers 18 and 19 materially aid in 90 taking up or compensating for any contraction or expansion and prevent injury to the cylinder or cracking or breaking of the latter when subjected to different temperature 95 variations. 100

The cross head 7 is applied to the operating mechanism as usual through the medium of oppositely disposed bearings or bearing openings 20, into which extend the connecting means of the actuating mechanism, 105 the said cross head being held in fixed as-

sociation with the connecting means through the medium of set screws 21 inserted in the open end of the cross head. The said cross head also has the usual grooves 22 for packing rings for a purpose which will be readily understood. It will be seen that the plunger 5 may be readily assembled with the end of the cross head, and when found necessary the nut 14 may be removed or withdrawn from the threaded end 13 of the bolt 9, to permit separation of the cylinder 5 with the bolt from the cross head.

The improved device, and particularly the plunger 5, is intended to be used in any form of pump to which the same may be adapted and particularly where a non-corrosive plunger, or one which will resist erosion, will have greater efficiency of operation from a standpoint of durability. It will also be seen that in the present improved form of plunger or piston the porcelain cylinder 5 is not cast or directly secured to the bronze bolt 9 but has the interposed filling 17 of a cement which will be adapted for the purpose of anchoring the bolt 9 within the center and at a distance from the inner wall of the bore 8 of the porcelain cylinder 5. From the foregoing it will be understood that the cylinder 5 is intended to be formed of any material other than metal, to resist deterioration by various fluids carrying silt, acidulous components or other elements, to adapt the cylinder for use in pumps that may have a particular application or service different from pumps particularly constructed and adapted for pumping water.

It is also proposed to modify the dimensions and general proportions of the plunger and cross head, to adapt the same to various applications without sacrificing the essential details of construction embodying the features of the present invention.

What is claimed as new is:

- 45 1. A pump plunger consisting of a hollow non-metallic cylinder, a bronze bolt extending through the center of the cylinder and having spiral grooves therein, the outer end of the bolt being provided with a head and the inner end having screw threads and a securing nut, a cement filling interposed between and around the bronze bolt and the cylinder, a lead washer between the outer headed end of the bolt and the end of the cylinder and cement filling, a cross head through which the inner screw-threaded extremity of the bolt extends, the cross head being removably secured to the bolt by the nut which is disposed interiorly thereof, and a wood fiber washer interposed between the inner end of the porcelian cylinder and the cross head and through which the bolt also extends.
- 60 2. The combination with a cross head, of a pump plunger secured thereto and con-

sisting of an outer surrounding non-metallic cylinder with a metallic bolt interiorly fixed thereto and having a head at its outer end and its inner end screw threaded and provided with a nut for securement to one end of the cross head, a lead washer between the outer headed end of the bolt and the end of the cylinder, and a wood fiber washer between the inner end of the cylinder and the cross head and surrounding the bolt.

3. The combination with a cross head, of a pump plunger removably secured thereto, the plunger consisting of an outer non-metallic cylinder to operatively fit within a pump, metallic securing means extending completely through and held immovable in the cylinder and projected beyond the inner end of the latter and attached to the cross head, and a non-corrosive metal washer interposed between the outer end of the bolt and the outer end of the cylinder.

4. The combination with a cross head, of a pump plunger consisting of an outer vitreous cylinder, a metallic securing bolt of a non-corrosive nature extending the full length of and secured in the cylinder and having an outer headed end and an inner screw-threaded and nutted end connected to the cross head, and a wood fiber washer interposed between the inner end of the vitreous cylinder and the cross head around the bolt.

5. The combination of a cross head having a seat formed in one end with a central bore therethrough communicating with the said seat, a pump plunger comprising an outer non-metallic cylinder and an inner non-corrosive metal bolt extending the full length thereof and beyond the inner end and secured in the cylinder against movement, the bolt having an outer headed end exerting a pressure against the outer terminal of the cylinder and also provided with an inner screw-threaded and nutted end for securement to the cross head, the inner extremity of the cylinder being closely held within the seat of the cross head by the bolt.

6. The combination of a cross head having a central seat opening through one end and a bore extending therethrough and communicating with the seat, a wood fiber washer disposed against the inner end wall of the seat, and a pump plunger of vitreous material closely fitted in the seat against the said washer at its inner end and also having a non-corrosive metal bolt secured therein and extending rearwardly therefrom through the bore of the cross head and firmly connected to the latter.

7. The combination of a cross head having a seat recess in one end and a central bore opening into said recess, a pump plunger consisting of an outer non-metallic cylinder, a non-corrosive metal bolt extending through the center of the cylinder and

having an outer headed end and also grooves throughout the length thereof, the inner end of the bolt being screw-threaded and nutted and extending through the bore of the cross head and secured to the latter, a cement filling between the bolt and the cylinder, a wood fiber washer interposed between the inner end wall of the seat and the inner

terminals of the cylinder and cement filling, and a lead washer interposed between the head of the bolt and the outer terminals of the cylinder and cement filling

In testimony whereof I have hereunto set my hand.

JOHN W. STEWART.
